UNITED STATES PATENT OFFICE.

CHARLES H. STEPHAN, OF SPRINGFIELD, OHIO.

ICE-CREEPER.

1,195,866.

Specification of Letters Patent. Patented Aug. 22, 1916.

Application filed February 29, 1916. Serial No. 81,242.

To all whom it may concern:

Be it known that I, CHARLES H. STEPHAN, a citizen of the United States, residing at Springfield, in the county of Clark and State of Ohio, have invented new and useful 5 Improvements in Ice-Creepers, of which the following is a specification.

This invention relates to anti-slipping devices for shoes and has particular application to an ice creeper.

10 The chief characteristic of this invention resides in the provision of a device of this character which is in the form of a rubber, slip or the like, whereby the same may be 15 readily attached and detached to or from the shoe.

20 An important characteristic of this invention is to provide an ice creeper having the anti-slipping elements so arranged thereupon as to effectively protect the sole 25 of the shoe against the liability of the elements penetrating the same.

Other objects of the invention will appear as the specification is read in connection 25 with the accompanying drawings and in which:—

Figure 1 is a side elevation of a rubber or over-shoe constructed in accordance with my invention showing a portion thereof broken 30 away. Fig. 2 is a side elevation of a modified form of my invention showing the same in the form of a slip or sandal. Fig. 3 is a further modification of my invention showing the same in the form of a heel section.

35 Referring to the drawings in detail and more particularly to Fig. 1, A designates a rubber over-shoe of any suitable form and which is constructed of any suitable material such as rubber "Neolin" or the like.

40 Mounted within the rubber A and lying contiguous to the inner face of the bottom thereof, is an inner sole 1, which is formed of any suitable rigid material such as steel or the like and is of a shape corresponding 45 to the sole of the shoe. Secured upon the under side of the inner sole 1 at the ball and the heel portions thereof are a transverse series of spurs 2, the same having enlarged heads 3, which are welded or otherwise se-

50 cured to the sole and having the body portion thereof of conical configuration as at 4. The spurs 2 are adapted to extend through openings 5 formed in the sole of the rubber, the openings having their walls provided 55 with eyelets 4' which are formed of any suitable metal, whereby the walls will be

reinforced to prevent the spurs from breaking or tearing the same.

It will be noted that the spurs 2 have the enlarged heads 3 interposed between the inner sole 1 and the sole of the rubber which further assists in holding the spurs upon the inner sole and prevents the spurs from being broken at their connection with the inner sole.

65 It will be seen from the foregoing construction that I have provided an ice creeper which may be readily detached and attached to and from the shoe, the spurs 2 being so mounted as to effectively prevent them from 70 piercing the sole of the shoe.

75 Referring more particularly to Fig. 2 I have shown my invention applied to a slip or sandal B. This slip B is of any common construction, the same being provided with the usual gripping flange 7, the ends thereof terminating on opposite sides of the sandal as at 8. The ends 8 are each provided with eyes which are adapted to receive the ends of suitable fastening means such as a strap 9 and a buckle 10. The inner side of the slip B is provided with a steel inner sole 11, the same being of a contour corresponding to that of the slip and is formed with a series of studs or spurs 2 on the under side thereof, 80 these spurs being of such construction as that shown in Fig. 1. The spurs 2 extend through the sole of the slip in a manner similar to that shown in Fig. 1 and the openings through which the studs extend 85 are provided with eyelets as shown in Fig. 1. To further retain the slip upon the shoe, I have provided the vertical sides thereof with a band of rubber or any other suitable material 11' which is arranged transversely of 90 the slip and has its opposite extremities secured to the vertical sides thereof as shown in the drawings. It will be seen from this construction that I have provided a slip which is formed with the steel inner sole and 95 the spurs whereby an efficient means is provided for preventing the slipping of the shoe when applied thereto.

100 In Fig. 3 I have shown another modification of my invention including a heel portion C which is adapted to engage the heel of the shoe and is secured thereto by means of a securing member 12.

105 It is thought from the foregoing description taken in connection with the accompanying drawings, that the construction and operation of my device will be apparent to 110

those skilled in the art without further description, and that minor changes in size, shape, proportion and minor details of construction may be made without departing from the spirit and scope of the appended claims.

What I claim is:—

1. An ice creeping attachment for shoes comprising an outer sole formed of flexible material, an upstanding gripping flange formed on the edge of the outer sole, said flange being inclined inwardly and having its upper edge flared outwardly, and a rigid inner sole having its edges engaging said flange, and spurs formed on the bottom of the inner sole and extending through and beyond said outer sole.

2. An ice creeping attachment for shoes comprising an outer sole formed of flexible material and having upward extending portions adapted to contact with the edges of the tread surface of a shoe on which the device is worn, a rigid inner sole having its edges engaging the upward extending portions of the outer sole, and spurs formed on the bottom of the inner sole and extending through and beyond the outer sole.

In testimony whereof I affix my signature in presence of two witnesses.

CHARLES H. STEPHAN.
